UNITED STATES PATENT OFFICE.

WALTER A. HOUGH, OF LYONS, NEW YORK.

RAILWAY ROAD-BED.

1,073,046.

Specification of Letters Patent.

Patented Sept. 9, 1913.

Application filed May 21, 1913. Serial No. 769,065.

To all whom it may concern:

Be it known that I, WALTER A. HOUGH, a citizen of the United States, residing at Lyons, in the county of Wayne and State of New York, have invented new and useful Improvements in Railway Road-Beds, of which the following is a specification.

The present invention relates to beds for railway rails.

10 In carrying out my invention it is my purpose to provide a bed for the reception of railway rails which will at all times be retained level so that the same will provide a perfectly level surface for the rails received thereon, and so prevent the downward sagging and chipping of the lower ends at the joints of the rails, thus materially adding to the life of the rails as well as to the comfort of the traveling public.

15 A further object of the invention is the provision of a roadbed constructed of reinforced concrete arranged in sections having simple but effective means for connecting the sections, the bed having continuous channels for the reception of cushion members upon which the rails are received, the said cushion members being sustained within their channels or pockets through the medium of bolt members which are embedded within the plastic roadbed, and which project above the wooden cushion members so as to receive metallic rail plates, whereby the rails may be attached to the roadbed without the employment of the ordinary spikes.

20 A still further object of the invention is the novel arrangement of a roadbed made up of a plurality of sections and having depressions providing channels or pockets for the reception of wooden cushion members upon which the rails rest, the said cushion members being also made up of a plurality of sections, and certain of said sections straddling the joints of the roadbed sections to prevent the lateral movement of said sections as well as providing a connection for the sections.

25 With the above recited objects in view and others which will appear as the nature of the improvement is more fully understood, the improvement resides in the construction, combination and operative arrangement of

parts set forth in the following specification and falling within the scope of the appended claims.

55

In the drawings there has been illustrated a satisfactory reduction of my improvement to practice, but the important instrumentalities thereof may be varied, and so it is to be understood that the showing is merely illustrative and that I am entitled to such changes in form, construction, etc., as falling within the scope of my claims.

60 In the drawings: Figure 1 is a top plan view of a roadbed constructed in accordance with my improvement and showing rails secured thereto, Fig. 2 is a plan view of a portion of the roadbed with the rails detached, Fig. 3 is a plan view of some of the sections of the roadbed as well as some of the units of the wood cushion members partly separated and illustrating the dowel connecting members of the roadbed sections and cushion members and indicating, by the dotted lines, the pockets for the reception of 65 the dowels, Fig. 4 is a transverse sectional view on the line 4-4 of Fig. 1, Fig. 5 is a horizontal sectional view on the line 5-5 of Fig. 1, Fig. 6 is a similar view on the line 6-6 of Fig. 1, and Fig. 7 is a perspective 70 view of one of the cross plates which may be employed.

75 Referring now to the drawings in detail, the numeral 1 designates the roadbed in its entirety. The bed is made up of a desired number of sections or units, each having its body portion constructed of reinforced concrete and embodying side members 2 provided with transverse connecting members 3. The connecting members 3 may be formed 80 of metal, or of plastic material within which are embedded rods 4 which project into the opposite sides 2. The sides 2 each comprise a substantially rectangular member, and each of said sides has its upper face centrally formed with a continuous channel 5. The channel 5 provides a lower horizontally straight wall and angular side walls, thus being of a substantially rectangular formation, and certain of the reinforcing elements 85 of the sides 2 comprise vertically extending headed threaded elements 6, which are arranged in pairs and extend a suitable distance above the upper faces of the sections.

95

100 With the above recited objects in view and others which will appear as the nature of the improvement is more fully understood, the improvement resides in the construction, combination and operative arrangement of

2, adjacent the opposite side walls of the channel 5. One of the ends of each of the sections 2 has its side member provided with projecting dowels 7, while the co-acting member is provided with recesses 8 for the reception of dowels upon the co-acting unit of the roadbed.

The numerals 9 designate the cushion members upon which the rails R—R rest. 10 These members 9 are preferably formed of wood, and are of a rectangular shape and of a size corresponding to that of the channels 5, so that the side walls as well as the bottom face of the cushion members 9 contact with the walls of the channels. The members 9 are provided with suitable openings arranged adjacent the longitudinal sides through which the bolt members 6 project, and it will be noted, by reference 15 to the several figures of the drawings, that the cushion members 9 are adapted to straddle the joint of the units of the roadbed, so that the said cushions provide means in addition to the dowels 7 and recesses 8 for retaining the units of the roadbed in proper alinement. The bolts 6 also properly project through suitable openings in metallic plates 10, the said plates being each provided with an integrally formed rail 20 flange-engaging lip 11 which is adapted to engage with the said rails upon one side of the rails. The lips 11 may be staggered with relation to the roadbed, that is, one of the lips may be arranged to engage with the outer base flange of the rails R, and the pair of plates to the opposite sides of this plate may have their lips engage with the inner flanges of the rails. However, I have found 25 it preferable to employ in addition to the lips 11, clips 12 each of which being received upon the bolt 6 opposite to that passing through the opening adjacent the lip 11. These clips are provided with angular rail-engaging lips 13, and the clips are 30 sustained upon the plates through the medium of nuts 14 which engage with the bolts 6, to which the clip is attached. Nuts 15 are also secured to the opposite rods 6, so that the plate 10 is effectively sustained 35 upon the roadbed. If desired, the plates 10 may be of a greater width than that of the cushion members 9, so that the ends of the plates will overlie the upper faces of the sides 2 of the roadbed and tend to firmly 40 compress the cushion members within the channels of the roadbed.

From the foregoing description, taken in connection with the accompanying drawings, the simplicity of the device, as well as 45 the advantages thereof, will it is thought, be perfectly apparent to those skilled in the art to which such inventions appertain without further detail description.

The members 7 may if desired be in the 50 form of lag screws, so that the teeth thereof

will be firmly embedded within the walls of the openings 8.

The portions of the sides 2 provided adjacent the channel 5 are projected a suitable distance above the members 9, the said projections, indicated by the letters A and B being provided to serve as guards for the rails R and the advantages thereof will be 55 fully understood.

Having thus described the invention, 75 what I claim as new is:

1. A roadbed for railway rails constructed of reinforced plastic material, the said roadbed comprising a plurality of jointed similar units or sections, each of said units comprising substantially rectangular side members and spaced connecting members, each of said side members having its upper face formed throughout its entire length with a centrally arranged longitudinally extending channel, certain of the metallic reinforcing elements of the bed including threaded members which project through the channel, rail-receiving cushion members adapted to be arranged within the channels, said cushion members being provided with openings for the reception of the threaded reinforcing members and adapted to overlap the ends of the units, and nuts for the projecting threaded reinforcing members. 90

2. A bed for railway rails constructed of reinforced plastic material and made up of a plurality of similar co-acting sections or units, each of the units comprising elongated rectangular side members having reinforced plastic connecting and spacing members, means arranged upon the ends of the sides of each of the units for interlocking the said unit with the co-acting unit, each of the sides having centrally arranged channels extending longitudinally the entire length of said units, threaded members projecting through the lower walls of the channel, cushion members adapted to fill the channels, said cushion members arranged to straddle the joints of the units of the roadbed and having openings for the passage of the threaded members, plates having rail-engaging lips connected with the threaded members, rail clips connected with the threaded member arranged adjacent the lip of the plate, and nuts for the threaded members. 105

3. A roadbed for railway rails made up of a plurality of companion-shaped members 120 each comprising sides and connected members for the sides, dowels upon the ends of the sides of one of the units and adapted to enter openings in the ends of the companion units, the sides being channelled 125 longitudinally, cushion members arranged within the channels and adapted to break the joints of the units of the roadbed, means for securing the cushion members together, means for securing the rails upon the 130

cushion members, and the roadbed units adjacent their channels being projected to provide rail guards.

4. A roadbed for railway rails made up of a plurality of companion-shaped members each comprising sides and connecting members for the sides, dowels upon the ends of the sides of one of the units and adapted to enter openings in the ends of the companion units, the sides being channeled longitudinally, cushion members arranged within the channels and adapted to protect the joints of the units of the roadbed, means for securing the cushion members together, and means for securing the rails upon the cushion members.

5. A roadbed for railway rails made up of a plurality of companion shaped members comprising sides and connecting members for the sides, dowels upon the ends of the

sides of one of the units and adapted to enter openings in the ends of the companion units, the sides being channeled longitudinally, cushion members arranged within the channels and adapted to protect the joints of the units of the roadbed, dowels upon the ends of one of the cushion members and adapted to enter openings in the end of the companion cushion members, means for securing the cushion members upon the roadbed, and said means adapted to also retain the rail engaging members upon the cushion members and upon the roadbed.

In testimony whereof I affix my signature in presence of two witnesses.

WALTER A. HOUGH.
